UNITED STATES PATENT OFFICE.

JOSEPH DAVIDOFF, OF BROOKLYN, NEW YORK.

HOIST-GEARING.

1,273,747.

Specification of Letters Patent. Patented July 23, 1918.

Application filed October 15, 1917. Serial No. 196,692.

To all whom it may concern:

Be it known that I, JOSEPH DAVIDOFF, a citizen of the United States, and a resident of the city of New York, borough of Brooklyn, in the county of Kings and State of New York, have invented a new and Improved Hoist-Gearing, of which the following is a full, clear, and exact description.

10 The object of the invention is to provide a new and improved portable hoisting machine more especially designed for use on dwellings and like structures for hoisting ash cans and other loaded receptacles out of 15 a cellar onto the sidewalk and to return the empty receptacles to the cellar. Another object is to permit of conveniently removing the hoisting machine after use to be out of the way of the passing pedestrians.

20 In order to accomplish the desired result use is made of a frame, a hollow shaft journaled in the said frame, manually controlled means for turning the said hollow shaft, a hoisting drum mounted to rotate loosely on 25 the said hollow shaft and provided with an internal gear wheel, a single and a double gear wheel mounted on the said frame and in mesh with the said internal gear wheel, a pinion slidable on the said hollow 30 shaft and turning therewith, and manually controlled shifting means connected with the said pinion to shift the same lengthwise on the said hollow shaft into engagement with either of the said single gear wheels or the 35 double gear wheel.

A practical embodiment of the invention is represented in the accompanying drawings forming a part of this specification, in which similar characters of reference indicate corresponding parts in all the views.

40 Figure 1 is a side elevation of the hoisting machine;

Fig. 2 is a plan view of the same;

Fig. 3 is an enlarged sectional side elevation of the same on the line 3—3 of Fig. 4; and

Fig. 4 is an inverted sectional plan view of the same on the line 4—4 of Fig. 3.

The frame 10 of the hoisting machine is 50 adapted to be mounted to swing on a bracket 11 by the use of a pivot pin 12 held removably on the bracket 11. The bracket 11 is bolted or otherwise secured to the side of a house or other support 13 at a point above 55 the opening in the sidewalk leading to a cellar. On the frame 10 is journaled a hollow

shaft 14 on which is mounted to turn loosely a hoisting drum 15 provided with the usual peripheral groove 16 engaged by a hoisting rope 17 for hoisting a filled receptacle from 60 the cellar to the sidewalk or lowering an empty receptacle from the sidewalk into the cellar, as hereinafter more fully explained. The drum 15 is provided with two flanges 18 and 19, of which the flange 19 is provided with an outwardly extending rim 20 provided on its inner face with an internal gear wheel 21 in mesh with two gear wheels 22 and 23, of which the gear wheel 22 rotates loosely on a stud 24 secured to the frame 10. 65 The other gear wheel 23 forms part of another gear wheel 25 of larger diameter thus providing a double gear wheel mounted to turn loosely on a stud 26 attached to the frame 10. The gear wheel 25 extends outside of the rim 20 and is thus out of the plane of the other gear wheel 22, and either gear wheel 25 or 22 is adapted to be engaged by a pinion 30 mounted to turn with and to slide lengthwise on the hollow shaft 14. For 70 this purpose use is made of a key and keyway 31 (see Fig. 3), and use is also made of a cotter pin 32 held on the pinion 30 and extending through a longitudinal slot 33 formed in the hollow shaft 14. The cotter 75 pin 32 extends into an opening formed in a shifting rod 35 mounted to slide lengthwise within the hollow shaft 14. The rear end of the shifting shaft 35 extends beyond the rear end of the hollow shaft 14 and on this 80 rear end of the shifting shaft 35 is arranged a shifting collar 40 engaged by one end of a shifting lever 41 fulcrumed at 42 on a bracket 43 secured to or forming part of the frame 10. A handle 44 is connected 85 with the shifting lever 41 and is mounted to slide in an open bearing 45 attached to the frame 10. The handle 44 is provided with two notches 46 and 47 adapted to drop into the bearing to hold the handle 44 in either 90 of its extreme positions.

On the forward end of the shaft 14 is secured a wheel 50, provided at its peripheral face with spaced apertures 51 adapted to be engaged by a spring-pressed tapering pin 105 52 mounted to slide in a crank arm 53 having its hub 54 partly divided and mounted to turn loosely on the hollow shaft 14 as the fulcrum. The spring pressed pin 52 is provided with a handle 55 adapted to be taken 110 hold of by the user to slide the spring pressed pin 52 outward out of engagement

with the corresponding aperture 51 and to then engage the handle 55 with an angular notch 56 formed in the crank arm 53 to hold the pin 52 in withdrawn position when 5 it is desired to let the drum 15 run loosely for lowering a load. Normally, however, the pin 52 is in engagement with an aperture 51 of the wheel 50 and when the crank arm 53 is turned in the direction of the 10 arrow α , shown in Fig. 1, then a rotary motion is given to the ratchet wheel 50 and to the hollow shaft 14, the shaft 35 and the pinion 30. The hub 54 of the crank arm 53 is held in position on the hollow shaft 14 15 by a cap nut 57 screwing on the forward end of the hollow shaft 14.

On moving the handle 44 forwardly a rearward sliding movement is given to the shifting shaft 35, whereby the pinion 30 is 20 moved into engagement with the gear wheel 25, and when the crank arm 53 is now turned a rotary motion is transmitted to the double gear wheel 25, 23, and as the latter is in mesh with the internal gear wheel 21 it is 25 evident that the drum 15 is rotated in the direction of the arrow y to wind up one end of the rope 17 with a view to raising the ash can or other heavy load out of the cellar up onto the sidewalk. In case a light load is 30 to be raised then the handle 44 is shifted farther forward to move the pinion 30 out of mesh with the gear wheel 25 and into mesh with the gear wheel 22, and when the crank arm 53 is now turned in the direction 35 of the arrow α then a rotary motion is given to the drum at a higher rate of speed and likewise in the direction of the arrow y to raise a lighter load.

When the pinion 30 is in mesh with the 40 gear wheel 25 and it is desired to disconnect said pinion from the gear wheel 25 with a view to allow the drum 15 to rotate loosely then the handle 44 is moved rearwardly a short distance to move the pinion 30 forwardly into a recess 60 formed in the frame 10. When the pinion 30 is, however, in mesh with the gear wheel 22, as previously explained, and it is desired to allow the drum 15 to rotate loosely for lowering an 45 empty can then a further forward movement is given to the handle 44 to move the pinion 30 rearwardly into a recess 61 formed in the front face of the drum 15 (see Fig. 4). By this arrangement it is not necessary to shift 50 the pinion 30 a long distance when it is desired to move it out of engagement with either gear wheel 25 or the gear wheel 22 to allow the drum to rotate loosely for lowering an empty receptacle into the cellar.

55 In order to prevent too fast unwinding of the rope 17 when lowering the empty receptacle into the cellar, use is made of a brake band 70 extending around the rim 20 and secured at one end by screws 71 or other 60 fastening means to the frame 10 (see Figs.

3 and 4). The free end of the brake band 70 is provided with an open hook 72 into which extends a brake lever 73 fulcrumed at its rear end at 74 to the frame 10. The forward end of the lever 73 extends within 70 the path of the crank arm 53 so that when the latter is turned in the direction of the arrow α it lifts the brake lever 73, then passes the same and allows it to return to normal position. When, however, the crank arm 53 is swung in the inverse direction of the arrow α then it bears down on the brake lever 73 to draw the brake band 70 tight on the rim 20 thus braking the hoisting drum 15. When the crank arm 53 bears on the 80 brake lever 73 the operator can retract the pin 52 relative to the wheel 50 to allow the drum 15 to run loosely on the hollow shaft 14 when lowering an empty receptacle into the cellar, the speed of the drum being controlled by the brake band.

85 In order to permit easy and safe shifting of the shaft 35 and pinion 30, as above described, the operator swings the crank arm in the direction of the arrow y to bear down 90 on the brake lever 73 and thus apply the brake band 70 on the rim 20 thereby slightly turning the drum 15 and then holding it against turning in either direction. It will be noticed that the slight turning of the 95 drum 15 frees the internal gear wheel relative to the wheels 22 and 23 to allow moving the pinion 30 easily into or out of mesh with either of the gear wheels 22 or 25, as above described. Thus the operator can shift the 100 shaft 35 and the pinion 30 even when a load is suspended on the rope 17, as the drum 15 is held against turning by the brake mechanism controlled by the crank arm 53.

105 After the hoisting of the filled receptacle and the lowering of the empty receptacle is accomplished, the user withdraws the pivot pin 12 from the bracket 11 and the frame 10 to allow removal of the hoisting machine and storing thereof until it is desired to 110 again use the same at a future time. It will be noticed that by the arrangement described, the hoisting machine is portable and can be readily placed in position for use or removed to be completely out of the way of 115 the pedestrians passing along the sidewalk.

120 From the foregoing it will be seen that the operator by having hold of the crank arm 53 can turn the hoisting drum 15 for hoisting a light or a heavy load from the cellar to the sidewalk, and the crank arm 53 also serves to control the brake mechanism to allow of checking the speed of the drum 15 when lowering an empty can or receptacle from the sidewalk to the cellar.

125 Having thus described my invention, I claim as new and desire to secure by Letters Patent:—

1. A hoisting machine, comprising a frame, a hollow shaft journaled on the said 130

- frame, manually controlled turning means for turning the said shaft, a hoisting drum mounted to rotate loosely on the said hollow shaft and provided with an internal gear 5 wheel, a single and a double gear wheel mounted on the said frame and in mesh with the said internal gear wheel, a pinion slideable on the said hollow shaft and turning therewith, and manually controlled shifting 10 means connected with the said pinion to shift the same lengthwise on the said hollow shaft into engagement with either the said single gear wheel or the double gear wheel.
- 15 2. A hoisting machine, comprising a frame, a hollow shaft journaled on the said frame, manually controlled turning means for turning the said hollow shaft, a hoisting drum mounted to rotate loosely on the 20 said hollow shaft and provided with an internal gear wheel, a single and a double gear wheel mounted on the said frame and in mesh with the said internal gear wheel, a pinion slideable on the said hollow shaft and turning therewith, a shifting shaft slideable 25 in the said hollow shaft, a pin connecting the said pinion with the said shifting shaft, and a shifting lever fulcrumed on the said frame and pivotally connected with the said 30 shifting shaft.
3. A hoisting machine, comprising a frame, a hollow shaft journaled on the said frame, manually controlled turning means for turning the said shaft, a hoisting drum mounted 35 to rotate loosely on the said hollow shaft and provided with an internal gear wheel, a single and a double gear wheel mounted on the said frame and in mesh with the said internal gear wheel, a pinion slideable on the said 40 hollow shaft and turning therewith, a shifting shaft slideable in the said hollow shaft, a pin connecting the said pinion with the said shifting shaft, and a shifting lever fulcrumed on the said frame and pivotally connected 45 with the said shifting shaft to shift the latter and with it the pinion to engage the said pinion with either the said single gear wheel or the double gear wheel, the said hollow shaft having a slot through 50 which extends the said pin.
4. A hoisting machine, comprising a frame, a hollow shaft journaled on the said frame, manually controlled turning means for turning the said hollow shaft, a hoisting drum 55 mounted to rotate loosely on the said hollow shaft and provided with an internal gear wheel, a single and a double gear wheel mounted on the said frame and in mesh with the said internal gear wheel, a pinion slideable on the said hollow shaft and turning therewith, manually controlled shifting 60 means connected with the said pinion to shift the same lengthwise on the said hollow shaft into engagement with either the
- said single gear wheel or the double gear 65 wheel, a brake band attached at one end to the said frame, and a brake lever fulcrumed on the said frame and engaging the free end of the said brake band, the said brake lever being controlled by the said turning means. 70
5. A hoisting machine, comprising a frame provided with a recess, a hollow drum shaft journaled in the said frame and extending centrally through the said recess, the said hollow shaft having a slot, a hoisting drum 75 mounted to turn loosely on the said hollow shaft and provided with an internal gear wheel and with a recess through which extends centrally the said hollow shaft, a single gear wheel in mesh with the said internal 80 gear wheel, a double gear wheel of which one is smaller than the other, the smaller gear wheel being in mesh with the said internal gear wheel, a pin mounted to slide on and to turn with the said hollow shaft 85 and adapted to engage either of the said recesses or the said single gear wheel or the larger gear wheel of the double gear wheel, a shifting shaft slideable in the said hollow drum shaft, a pin connecting the said pinion 90 with the said shifting shaft, the pin extending through the slot in the said recess, and means connected with the said shifting shaft to shift the latter lengthwise in the said 95 hollow shaft.
6. A hoisting machine, comprising a frame provided with a recess, a drum shaft journaled in the said frame, a drum mounted to rotate loosely on the said drum shaft and provided with an internal gear wheel and 100 with a central recess, the said drum shaft extending centrally through both recesses, a single gear wheel mounted on the frame and in mesh with the said internal gear wheel, a double gear wheel mounted on the frame 105 and having a small and a large gear wheel of which the small gear wheel is in mesh with the said internal gear wheel, a pinion mounted to turn with and to slide on the said drum shaft and adapted to engage 110 either of the said recesses, or the said single gear wheel or the large gear wheel of the double gear wheel, means for rotating the said drum shaft, and means for shifting the said pinion. 115
7. A hoisting machine, comprising a hoisting drum, a brake for the same and having a brake lever, a gearing for turning the said drum, and a pin and wheel mechanism having a demountable crank arm and connected 120 with the said gearing, the said brake lever extending into the path of the said crank arm.
8. A hoisting machine, comprising a drum, a brake mechanism for the said drum, a 125 gearing for rotating the said drum and having a shiftable member, means for shifting the said shiftable member, and a crank arm

for turning the said shiftable member and adapted to engage the said brake mechanism to apply the same for holding the drum against rotation while shifting the said shiftable member.

9. A hoisting machine, comprising a drum provided with an internal gear wheel, a gear wheel in mesh with the said internal gear wheel, a pinion adapted to be moved

in mesh with the said gear wheel, a crank arm for turning the said pinion, shifting means for moving the pinion in and out of mesh with the said gear wheel, and a brake mechanism for the said drum and controlled by the said crank arm to lock the drum in place while shifting the said pinion.

JOSEPH DAVIDOFF.
